UNITED STATES PATENT OFFICE.

RICHARD MORIS BRENNER, OF PALISADE, NEW JERSEY.

RACE-GAME APPARATUS.

1,203,474.

Specification of Letters Patent. Patented Oct. 31, 1916.

Application filed April 7, 1916. Serial No. 89,562.

To all whom it may concern:

Be it known that I, RICHARD M. BRENNER, a citizen of the United States, and a resident of Palisade, in the county of Bergen 5 and State of New Jersey, have invented a new and Improved Race-Game Apparatus, of which the following is a full, clear, and exact description.

The invention relates to race game apparatus such as shown and described in the Letters Patent of the United States, No. 1,011,563, granted to me on December 12, 1911.

The object of the present invention is to provide a new and improved race game apparatus for use in pleasure resorts, exhibition grounds and other places, and arranged to enable a number of players simultaneously to manipulate racing objects such as 15 figures representing horses, for instance, with a view to cause such racing objects to travel over different tracks thereby simulating a race, the winning of which is solely dependent on the skill of the players.

In order to accomplish the desired result, use is made of a plurality of racing tables, one arranged alongside the other and adapted to move forward and backward independent one of the other, and racing objects, one 20 for each racing table and placed on the rear end of the said racing tables and remaining stationary thereon during the forward strokes of the racing tables and to travel forwardly during the return strokes of the 25 said racing tables.

A practical embodiment of the invention is represented in the accompanying drawings forming a part of this specification, in which similar characters of reference indicate corresponding parts in all the views.

Figure 1 is a plan view of the race game apparatus; Fig. 2 is a side elevation of the same with parts in section, on the line 2—2 of Fig. 3; Fig. 3 is a sectional plan view 45 of the same on the line 3—3 of Fig. 2; Fig. 4 is an enlarged side elevation of the barrier and starter and the mechanism for operating the same, parts being shown in section; Fig. 5 is an enlarged inverted plan 50 view of one of the racing objects; Fig. 6 is an enlarged sectional plan view of two adjacent stopping devices for the racing objects at the forward ends of the racing tables and also showing diagrammatically the con-

nection with the annunciator; Fig. 7 is a 55 sectional side elevation of a portion of the race game apparatus in which the racing tables are actuated by electric motors; Fig. 8 is a diagrammatic view of the same; and Fig. 9 is an enlarged sectional side elevation 60 of the clutch mechanism for stopping the movement of the tables after a racing object has reached the goal.

The race game apparatus is mounted on a suitable support 10, preferably in the form 65 of a box having an open top 11 provided with longitudinally extending partitions 12 dividing the open top into spaces 13 in which are mounted a plurality of longitudinally extending narrow racing tables 14, 70 over which are adapted to travel racing objects 15 such as figures representing horses and jockeys or the like, as plainly indicated in Figs. 1, 2 and 5. The racing objects 15 start simultaneously from the rear ends 16 75 of the tables 14 and finish at the forward ends 17 of the said tables. The several tables 14 and the means for moving the same forward and backward are alike and it suffices to describe but one in detail. Each 80 table 14 is supported on sets of parallel links 20 having their upper pivots 21 attached to the under side of the table 14 while the lower pivots 22 adjustably engage the longitudinally extending slots 23 formed in 85 the sides of the support or stand 10. The links 20 are adjusted so that they stand in an approximately vertical position at the time the table 14 is at the end of its forward stroke while the links 20 swing downward 90 and rearward during the return stroke of the table 14, so that on the forward stroke the table 14 moves forward and upward and during the return stroke moves downward and rearward. The racing objects 15 are 95 so adjusted in weight that during the forward and upward stroke of the tables 14 they remain stationary on their tables while during the downward and rearward stroke the racing objects move forward from the 100 starting end 16 toward the finishing end 17.

The speed at which the tables 14 move forward and backward is controlled by a number of players corresponding to the number of the tables so that each player 105 controls the speed of a table, and hence the result of the race depends solely upon the skill and judgment of each player for the

reason that if the player moves his racing table at too slow a speed the racing object will move forward too slow to win the race, while if the player moves his racing table 5 too fast and becomes excited the racing objects are not liable to move forward at all but, owing to the excessive vibration created in moving the table too fast, commence to dance or fall and thus are taken out of the 10 race.

In order to accomplish the desired result, the under side of each racing table 14 is provided near its forward end with a depending bracket 30 connected by a pitman 31 with a 15 wrist pin 32 held on a beveled gear wheel 33, the shaft 34 of which is journaled in a suitable bearing 35 attached to the stand 10. The bevel gear wheel 33 is in mesh with a pinion 36 secured on the forward end of a shaft 37 20 journaled in suitable bearings 38 attached to the stand 10, and the rear end of this shaft 37 is provided with a pinion 39 in mesh with a bevel gear wheel 40 secured at the inner end of a transverse shaft 41 journaled 25 in suitable bearings 42 forming part of the stand 10. The forward ends of the shafts 41 extend into a separate chamber 43 arranged at the front of the stand 10, and the forward end of each shaft 41 is provided 30 with a bevel gear wheel 44 in mesh with a bevel pinion 45 secured on the lower end of a shaft 46 extending upward through the top 11 to the upper surface thereof. The shaft 46 is journaled at its lower end in a 35 bearing 47 attached to the stand 10, and the upper end of the shaft is journaled in the top 11. On the upper end of the shaft 46 is secured a crank disk 48 having a crank handle 49 under the control of a player to 40 enable the latter to turn the shaft 46 and consequently the gearing described so that the pitman 31 imparts a forward and backward traveling motion to the table 14. The several disks 48 are arranged one alongside 45 the other at the front of the top 11 and are marked with consecutive numerals or similar indicating characters, as plainly shown in Fig. 1, to distinguish the several race tracks formed by the racing tables 14. Immediately in the rear of the disk are 50 arranged signs 50 having corresponding numerals, thus indicating which racing table a corresponding player is operating at the time.

55 In order to control the speed of the return and downward movement of each racing table 14, use is made of a spring 60 secured at one end to a bracket 61 attached to the under side of the corresponding table 60 14. The other end of the spring 60 is attached to a screw rod 62 mounted to screw in a nut 63 attached to the forward end of the stand 10. The operator on screwing the screw rod 62 inward or outward can decrease 65 or increase the tension of the spring 60 so

as to diminish or increase the speed of the return and downward movement of the racing table 14.

The top surface of each racing table 14 is provided with obstructions 70 and humps 71, the obstructions 70 being preferably beveled at their rear ends to a point. Each of the racing horses 15 has its fore legs 72 attached to a front plate 73 provided with tapering side edges terminating at the front 75 in a point (see Fig. 5), so that the said plates 73 on coming in contact with the pointed rear end of an obstruction 70 readily deflect the race horse without danger of the race horse being turned over on its side. 80 The rear legs 74 of the race horse 15 are preferably mounted to swing in a lateral direction on vertical pivots 75, and springs 76 are provided to hold the rear legs 74 in normal position. By the arrangement described, the rear legs 74 are free to swing sidewise so that in case a race horse 15 bumps against one of the obstructions 70 then a rear leg 74 is free to swing outward (see dotted lines in Fig. 5) thus increasing 85 the area of the supporting base of the race horse and preventing the same from toppling over in case of a forcible impact of the race horse with an obstruction 70. By reference to Fig. 2, it will be noticed that 90 the top surfaces of the tables 14 are below the partitions 12 to prevent one race horse from passing off its table onto an adjacent table. It will also be noticed that by the arrangement described the race horses during 95 their forward travel over the tables 14 are properly deflected on striking an obstruction 70 without causing the race horse to topple over. It will further be noticed that by having the hump 71 the player will experience considerable difficulty in safely getting the race horse over this hump. It will further be noticed that by the arrangement described the race horses although they have practically a uniform start are liable to be 100 more or less retarded in their forward movement over the several racing tables 14 owing to the varying speed with which the said tables are actuated by the different players.

A barrier 80, in the form of a rod or the like, extends across the several tables 14 immediately in front of the race horses or objects 15, and against the said barrier 80 when in lowermost position abut the heads of the race horses 15 so that the latter are 115 prevented from moving forward over the tables 14 until the barrier 80 is raised. The barrier 80 is of the same construction as the one shown and described in the Letters Patent above referred to, so that further description of the same is not deemed necessary, it being sufficient to state that the ends of the barrier are attached to vertically extending rods 81 pressed upward by a spring 82 but normally held against upward move- 120 125 130

ment by a retaining device 83 connected at one end with a spring 84 and at the other end with a shaft 85 under the control of the starter. Thus when the shaft 85 is turned 5 in one direction the rods 81 are released to allow the springs 82 to move the rods upward and thus raise the barrier 80 a distance above the racing objects 15 to allow the latter to pass under the barrier on the 10 players actuating the tables 14. One of the rods 81 is provided with an arm 90 controlling a spring-pressed rod 91 for operating an arm 92 on a figure 93 representing the starter and mounted on a stand 94. The 15 arm 92 carries a flag 95 so that when the barrier 80 moves up, the arm 92 and the flag 95 swing down, thus indicating that the race is on.

In order to indicate which of the racing 20 objects 15 first reaches the end 17 of the corresponding racing table 14 and wins the race, use is made of an annunciator 100 and stopping devices 101, one for each racing table 14 and located at the forward end 17 thereof. The stopping device 101 is mounted on spring-pressed rods 102 and is provided with a triangularly shaped, circuit closer 103 adapted to make contact through contact plates 104 and 105 connected by the 25 usual wires 106 and 107 with the annunciator 100. Thus when a racing object 15 abuts against the stopping device 101 it moves the latter forward against the tension of its spring rods 102, and the contact 30 103 finally moves into engagement with the contact plates 104 and 105 thus closing the circuit for the annunciator 100, which indicates the number of the winner of the race, the number corresponding to the number 35 on the corresponding operating disk 48.

Instead of using the actuating means above described, use may be made of an electric motor 120 for each racing table 14 (see Figs. 7 and 8). The shaft 121 of this 40 electric motor 120 is provided with a pinion 122 in mesh with a gear wheel 123 having a wrist pin 124 connected by a pitman 125 with a bracket 126 attached to the under side of the racing table 14. In the circuit 45 of the electric motor 120 is arranged a rheostat 130 under the control of a player to control the speed of the corresponding motor so that the motor for each racing table 14 can be run at a speed to suit the 50 player and hence one player may be enabled to move the racing object faster over the table than another, the same as above described relatively to the several players rotating the crank disks 48 at different 55 speeds.

The operator in charge of the race game apparatus stops the movement of the several tables as soon as one racing object 15 has reached the goal and won the race, and 60 for this purpose the following arrangement

is made, special reference being had to Figs. 3 and 9: On each of the shafts 41 is secured a brake wheel 140 adapted to be engaged at its peripheral face by a brake band 141 having one end 142 secured to the stand 10. The other end 143 of the brake band 141 is engaged by a collar 144 secured on a rod 145 extending lengthwise within the stand 10 so as to engage all the brake bands, as will be readily understood by reference to Figs. 3 and 9. A spring 146 is mounted on the rod 145 and presses with its ends against the ends 142 and 143 of the brake band 141 to normally hold each brake band in open position. One end of the rod 145 is pivotally connected with a hand lever 147 under the control of the operator in charge of the apparatus. The lever 147 is fulcrumed at its lower end at 75 148 on a notched segment 149 attached to the stand 10, and the said lever extends through a slot 150 arranged in the top 11 of the stand 10 at the rear end thereof. Normally the brake bands 141 are in open position but as soon as one of the racing objects 80 15 reaches the goal then the operator imparts a swinging motion to the hand lever 147 to the right to shift the rod 145 in the same direction thereby engaging the brake bands 141 with the brake wheels 140 to 85 brake the shafts 41 and thus gradually bring the tables 14 to a stop. It is understood that the several players cease to rotate the crank disks 48 as soon as the brake bands are applied. 90

The hand lever 147 is adapted to be locked in braking position by a pawl 151 fulcrumed on the lever 147 and engaging the notched segment 149. The pawl 151 is connected by a spring-pressed rod 152 with a releasing lever 153 fulcrumed on the hand lever 147 to allow the operator in charge to release the lever 147 whenever it is desired to release the brake band 141 from the brake wheels 140. For the apparatus equipped 100 with motors 120, use is made of a switch 160 (see Fig. 8) under the control of the operator in charge of the apparatus for breaking the motor circuits of the several motors simultaneously to stop the movement of the 105 tables 14 as soon as one of the racing objects 110 has reached the goal.

The operation is as follows: Assuming that the brake lever 147 is in released position, as shown in Fig. 9, and the barrier 80 is down 115 and each of the players has taken position opposite the crank disk 48, the operator in charge places the racing objects 15 on the rear ends of the several tables 14, as plainly shown in Fig. 1, and then the operator actuates the shaft 85 to raise the barrier 80 and to cause the starter 93 to drop the flag 95 thus indicating to the several players to start rotating the crank disks to cause the 120 tables 14 to swing forward and backward 125 130

and up on the forward movement, and down at the return movement, so that the racing objects 15 are caused to travel forward on the tables 14 and with more or less speed according to the speed given to the tables 14. As each racing table has unobstructed forward and backward reciprocating motion, the skill of each player is necessary for properly moving the racing objects forward on the tables; thus if a racing table is oscillated too slow the racing object thereon moves forward at too slow a speed to win the race, and if the racing table is moved too fast or the player becomes excited and turns the disk 48 too fast, the racing object is liable not to move forward at all, but, owing to the excessive vibration imparted to the table commences to dance or fall. If this takes place, such racing object is considered out of the race and removed from the corresponding table. As soon as one of the racing objects reaches the end 17 of its table first then the race is won by such racing object and the fact is announced by the annunciator 100 by the action of the racing object engaging the stopping device 101. It is understood that the annunciator is provided with a bell to sound an alarm as soon as the race is won. As soon as the alarm is sounded, the operator in charge of the apparatus throws the brake lever 147 over to the right to stop the movement of the tables 14 simultaneously, as previously explained.

Having thus described my invention, I claim as new and desire to secure by Letters Patent:

1. An amusement apparatus, comprising a plurality of racing tables adapted to move unobstructedly forward and backward, actuating means controlled by the players and having mechanical connections with the said racing tables to move the latter forward and backward independently one of the other and the same distance during each stroke, the speed of the said actuating means being controlled by the different players, and racing objects, one for each table and placed on the rear ends of the racing tables to travel intermittently forwardly on imparting motion to the said tables.

2. An amusement apparatus, comprising a plurality of racing tables arranged one alongside the other and adapted to move unobstructedly forward and backward and one independent of the other, a series of actuating means under the control of the different players and having crank connections with corresponding racing tables to move the latter forward and backward the same distance at each stroke and at a speed to suit the different players and racing objects, one for each table, and placed at the rear ends of the racing tables to travel intermittently forwardly during the return strokes of the racing tables.

3. An amusement apparatus, comprising a plurality of racing tables arranged one alongside the other and mounted to move unobstructedly forward and backward and one independent of the other, actuating means for each racing table and controlled by different players to impart motion to the racing tables at a speed to suit each individual player, racing objects, one for each table and placed on the rear ends of the racing tables to travel intermittently forwardly during the return strokes of the racing tables, and automatic annunciators, one for each table and having circuit-closing members at the forward ends of the said racing tables and in the paths of the said racing objects for any one of the latter to actuate the corresponding annunciator on the racing object reaching the forward end of the corresponding racing table.

4. An amusement apparatus, comprising a plurality of narrow racing tables, fixed separating partitions between adjacent racing tables and extending above the surfaces thereof, independent actuating means for each racing table and controlled by different players to impart a forward and backward motion to the racing tables at a speed to suit each individual player, and racing objects, one for each racing table and placed on the rear ends of the racing tables to travel intermittently forwardly thereon during the return strokes of the racing tables.

5. An amusement apparatus, comprising a stand having an open top provided with longitudinally extending partitions dividing the top into a series of spaces, a plurality of racing tables extending unobstructedly in the said spaces and mounted on the said stand to move unobstructedly forward and backward, actuating devices independent one of the other and one for each racing table, the actuating devices being controlled by different players to impart motion to the tables at speeds to suit each individual player, and racing objects, one for each table and placed on the rear ends of the said racing tables to travel forwardly thereon during the return strokes of the racing tables.

6. An amusement apparatus, comprising a stand having an open top provided with longitudinally extending partitions dividing the top into a series of spaces, a plurality of racing tables extending unobstructedly in the said spaces and mounted on the said stand to move unobstructedly forward and backward, actuating devices independent one of the other and one for each racing table, the actuating devices being controlled by different players to impart motion to the tables at speeds to suit each individual player, racing objects, one for each table and placed on the rear ends of the said tables to travel forwardly thereon during the return strokes of the racing tables, and an annunciator

having members at the forward ends of the racing tables and in the path of the racing objects to actuate the annunciator on a racing object reaching the forward end of its racing table.

7. An amusement apparatus, comprising a stand having an open top provided with longitudinally extending partitions dividing the top into a series of spaces, a plurality of racing tables extending unobstructedly in the said spaces and mounted on the said stand to move unobstructedly forward and backward, actuating devices independent one of the other and one for each racing table, each actuating device having a crank shaft, a pitman connecting the crank shaft with the corresponding racing table, a gearing for driving the said crank shaft, and a crank handle for each gearing, the several crank handles being controlled by different players to impart motion to the tables at speeds to suit each individual player, and racing objects, one for each table and placed on the rear ends of the said racing tables to travel forwardly thereon during the return strokes of the racing tables.

8. An amusement apparatus, comprising a plurality of racing tables arranged one alongside the other and mounted to move unobstructedly forward and backward and one independent of the other, actuating means for each racing table and controlled by different players to impart motion to the racing tables at a speed to suit each indi-

vidual player, racing objects, one for each table and placed on the rear ends of the racing tables to travel intermittently forwardly during the return strokes of the racing tables, and means for simultaneously stopping the movement of the several racing tables as soon as one of the racing elements has reached the forward end of its racing table first.

9. An amusement apparatus, comprising a plurality of narrow racing tables, separating partitions between adjacent racing tables and extending above the surfaces thereof, independent actuating means for each racing table and controlled by different players to impart a forward and backward motion to the racing tables at a speed to suit each individual player, racing objects, one for each racing table and placed on the rear ends of the racing tables to travel intermittently forwardly thereon during the return strokes of the racing tables, and means under the control of the operator in charge of the apparatus for simultaneously stopping the movement of the several racing tables on one of the racing elements reaching the goal first.

In testimony whereof I have signed my name to this specification in the presence of two subscribing witnesses.
